UNITED STATES PATENT OFFICE.

LEIGH R. QUIGLEY, OF SAN FRANCISCO, CALIFORNIA.

LOCK FOR GAS-METER CONNECTIONS.

1,067,549.

Specification of Letters Patent.

Patented July 15, 1913.

Application filed June 17, 1912. Serial No. 704,097.

To all whom it may concern:

Be it known that I, LEIGH R. QUIGLEY, a citizen of the United States, residing in the city and county of San Francisco and State 5 of California, have invented new and useful Improvements in Locks for Gas-Meter Connections, of which the following is a specification.

My invention relates to a means for locking 10 gas meter connections, such as the cocks or equivalent devices through which the gas is allowed to pass.

It consists in the combination with a cock 15 of an adjustable pin adapted to engage the cock, and a lock whereby the pin may be removed when desired.

It also comprises details of construction 20 which will be more fully explained by reference to the accompanying drawings, in which—

Figure 1 is a general view showing the application of my lock. Fig. 2 is a perspective view of the lock. Fig. 3 is a section of the lock on the end of the lock bar, showing 25 the key in position. Fig. 4 is a similar view showing the key removed. Fig. 5 is an enlarged end view of the lock 7.

A is a chamber of an ordinary cock having pipe connections through it, and the 30 plug B turnable transversely within the chamber of the cock to open or close such connections. The plug has a flattened portion 3, which is perforated as shown; and 4 is a pin which may be passed through the 35 perforation of the plug. One end of this pin has a head and it is held in place by a clamp 5, which surrounds one end of the cock and projects out so that its outer end stands in line with the hole through the 40 plug. In order to apply this clamp conveniently, it is made in the form of two segments which are pivoted together as at 6, and it may be opened so that it can be 45 passed over the portion to which it is to be secured; the two projecting arms are then brought together, leaving the clamp securely in place. As the plugs are of different lengths, in order to enable the pin to be passed through the hole in the plug, 50 which may be nearer to or farther from the center line of the cock, as shown, the projecting ends of the clamp are slotted radially so that the pin may be moved in or out, as may be desired. That portion of the 55 pin which passes through the plug may be cylindrical, and the portion which passes

through the slots in the clamp may be rectangular so that the pin can not be turned. It will be seen that when the pin has been passed through the clamp and the plug, it 60 will be impossible to turn the plug. In order to lock the pin in place, I have shown a head 7 having a hole bored axially in it to fit the end of the pin which has been passed through the end of the faucet plug. 65 At the inner end of this hole is made an annular enlargement 8, and within this lies a loose washer 9. This washer has a screw-threaded hole made in it which fits upon a corresponding screw 10 at the inner end 70 of the pin.

Normally the head 7 may be turned around without screwing or unscrewing the washer, so that after it has been screwed upon the end of the pin it can not be removed by any amount of turning. In order 75 to remove it, it is necessary to hold the washer and prevent its revolving while the head 7 may be turned around until the washer is unscrewed; the head can then be 80 removed and the pin taken out so as to allow the plug of the cock to be turned. In order to hold this washer, when necessary, I have shown a key which is formed by a pin 11 adapted to extend through a small hole 85 in the end of the head 7. When this pin is introduced it will pass between the periphery of the washer and the annular groove or channel in which it lies, and will thus prevent the washer from turning around 90 with the head. In this condition, if the head be turned it will immediately turn the washer and allow it to be moved.

The device is very simple, safe and easily manipulated.

Having thus described my invention, what I claim and desire to secure by Letters Patent, is—

1. A gas meter cock connection having a perforated, turnable plug, a two-part hinged clamp secured to one end of the cock having projecting arms arranged in line with the perforation in the plug, a pin adapted to pass through said perforation, means for attaching one end of the pin to the arms of 100 the clamp and a lock fitting the opposite end of the pin.

2. In a lock for gas meter connecting cocks and the plug thereof having a perforation through its outer end, a hinged two-part clamp adapted to be clasped around the body of the cock, said clamp having 110

ends which overlap and extend into line with the plug of the cock, and said ends being slotted radially, a pin having a head upon one end adapted to pass through the 5 slots in the clamp and through the hole in the plug, a lockable head secured to the opposite end of the pin, and means to lock or unlock said head.

In testimony whereof I have hereunto set my hand in the presence of two subscribing 10 witnesses.

LEIGH R. QUIGLEY.

Witnesses:

JOHN H. HERRING,
J. G. BUBB.
